LIGHT FIXTURE

Robert E. Lederer, Chicago, Ill., assignor to Hotel Sherman, Inc., Chicago, Ill., a corporation of Delaware

Application February 15, 1950, Serial No. 7,939

Term of patent 7 years

(Cl. D48—23)

To all whom it may concern:

Be it known that I, Robert E. Lederer, a citizen of the United States, residing at Chicago, in the county of Cook, State of Illinois, have invented a new, original, and ornamental Design for Light Fixture, of which the following is a specification, reference being had to the accompanying drawing, forming a part thereof, wherein:

Fig. 1 is a bottom plan view of a light fixture, showing my new design;

Fig. 2 is a side elevational view thereof, taken in the direction of line 2—2 in Fig. 1; and

Fig. 3 is a side elevational view taken in the direction of line 3—3 in Fig. 1.

The dominant features of my design reside in the portions shown in solid lines.

I claim:

The ornamental design for a light fixture, substantially as shown and described.

ROBERT E. LEDERER.
